Harold Ogden
HIS ATTORNEY

UNITED STATES PATENT OFFICE.

LLOYD V. H. ARMSTRONG, OF UPPER MONTCLAIR, NEW JERSEY, ASSIGNOR TO INGERSOLL-RAND COMPANY, OF JERSEY CITY, NEW JERSEY, A CORPORATION OF NEW JERSEY.

PNEUMATIC CONTROL FOR MARINE STEERING APPARATUS.

Application filed November 19, 1925. Serial No. 69,946.

This invention relates to marine steering apparatus and more particularly to pneumatic means for controlling such apparatus.

It is an object of this invention to enable the usual hand-operated steering apparatus for boats to be converted for operation by fluid actuated means such as compressed air or steam motors simply and inexpensively.

Other objects and advantages of the invention will be in part obvious and in part pointed out hereinafter.

In the drawings forming part of the specification and in which similar reference characters refer to similar parts,

Figure 1 is a side elevation of an apparatus for marine steering converted in accordance with the practice of the invention to be operated by motive fluid;

Figure 2 is a plan view of the automatic stop mechanism taken along the line 2—2 looking in the direction of the arrows;

Figure 3 is a vertical section through the throttle of the fluid operated motor, and

Figures 4, 5 and 6 are views of the automatic stop mechanism showing the mode of operation thereof.

Referring to the drawings and more particularly to Figure 1, A represents the deck of a boat upon which are bolted suitable uprights B supporting a drum C and a steering wheel D. A shaft E journaled in the uprights B forms the axis about which the drum C and the steering wheel D rotate. The rudder is operated by a suitable rope F wound about the drum C and guided over suitable pulleys G. In the ordinary operation of a steering gear of this type, the rudder is operated by a man at the wheel B turning the wheel and shaft E to rotate the drum C whereby the rope F is caused to pull the rudder in the desired direction.

On relatively large boats the wheel B is very difficult to manage and consequently the steering of such a boat requires great strength and endurance. However, the usual expense of installing the usual electric or steam apparatus is prohibitive. A simple apparatus for converting the steering gear to pneumatic or steam controlled is provided by this invention and includes a fluid actuated motor H preferably mounted below the deck A and having a sprocket J to operate a chain K passing over a relatively large sprocket L on the shaft E.

The motor H is controlled by a throttle valve shown in detail in Figure 3 which includes a sleeve O rotatable on a hollow tube P. A valve Q is adapted to seat at R within the tube P to cut off the supply of motive fluid from a pipe S attached by means of a threaded bushing T to the tube P. Normally, the valve Q is held to its seat by a coil spring U pressing against the head of the valve and the bushing T. To admit motive fluid to the motor the valve Q is raised from its seat by a pin V engaged by the sleeve O and adapted to ride on a heart-shaped cam surface of a guide W.

The casing of the motor H is provided with a pair of passages Y controlled by the tube P which has an exhaust passage Z cooperating with the passages Y. The inlet of motive fluid is controlled by the lifting of a plug b in the tube P. Motive fluid is admitted through a passage c in the plug b and through a port d to one or the other of the passages Y depending upon the direction of rotation of the tube P. In this manner motive fluid is admitted to the rotary valve e of the motor H. The reversing valve is described in greater detail in connection with a motor in U. S. Patent No. 1,566,096 granted to Francis A. Jimerson, Dec. 15, 1925. The reversing throttle valve for the motor H is manually controlled by a handle f attached to a vertically disposed rod g coupled to the sleeve O by a tube h keyed to the sleeve O and cut away as at k to accommodate the supply pipe S. The position of the handle f permits the steersman to stand in approximately the same position as when controlling the steering by means of the wheel D. Turning the handle f in one direction causes the motor H to rotate in one direction producing rotation of the drum C in one direction, and vice versa, turning the handle f in the opposite direction causes a reverse rotation of the drum C.

Normally holding the handle f to either of its operative positions causes the drum to turn continuously, whereupon the rudder is correspondingly turned. Means is provided to prevent the motor H from turning the rudder far enough to cause it to strike heavily against its stops. To this end there is provided a sprocket o engaging a chain p attached suitably at q to a cord r guided

over suitable idler pulleys s to a pulley t . The rope r and chain p are connected to form a continuous loop about the pulleys t and the sprocket o . The sprocket o is suitably connected or attached to the shaft E so as to rotate with the drum C . In the ordinary movement of the cord r the pulley t should not turn and to this end the cord r may be greased or otherwise prepared so as 10 to prevent frictional engagement with the pulley t . However, at positions of the cord r corresponding to the positions at which it is desired to stop the rudder suitable clips or engaging members u are attached 15 which are arranged to engage the stop members v on the pulley t . In the operation of the device when the rudder has reached the limiting position one of the stops u will strike the stop members v thereby engaging 20 the pulley t and turning the throttle valve to its off or neutral position as shown in Figures 4, 5 and 6. In Figure 4 the controlling handle f is shown turned to a position to turn the rudder. In this position the 25 cord r slips freely on the pulley t as the drum C rotates. In Figure 5 one of the members u is shown in a position at which the limiting position of the rudder has been

reached. One of the members u is about to engage one of the members v to turn the 30 handle f back to the position shown in Figure 6.

In this manner the motor H prevents its own operation beyond a danger point at which the rudder might be injured. The 35 apparatus described is relatively inexpensive and easy and safe to operate.

I claim:

In combination with the rope drum and its shaft of a marine steering apparatus, a 40 fluid actuated motor, operative connections between said motor and said shaft, a reversible throttle valve and means to prevent operation of the motor to rotate the drum beyond a point dangerous to the rudder, including a sprocket on said shaft and an endless chain and cord connection, a pulley on said throttle valve normally not engaged by said cord, and stop members on said pulley and said cord mutually engaging at 45 50 positions corresponding to dangerous positions of the rudder.

In testimony whereof I have signed this specification.

LLOYD V. H. ARMSTRONG.
